COMBINED CLOCK AND RADIO CABINET

John W. Mason, Glenview, and Ralph E. Hammer, Oak Park, Ill., assignors to Admiral Corporation, Chicago, Ill., a corporation of Delaware

Application August 9, 1957, Serial No. 47,287

Term of patent 14 years

(Cl. D56—4)

Fig. 1.

Fig. 2.

Fig. 3.

Fig. 4.

Fig. 5.

Fig. 1 is a front elevational view of a combined clock and radio cabinet, showing our new design;

Fig. 2 is a rear elevational view;

Fig. 3 is a top plan view;

Fig. 4 is a sectional view, drawn to an enlarged scale, indicated by line 4-4 of Fig. 2; and

Fig. 5 is a bottom plan view thereof.

The dominant features of our design reside in the portions shown in full lines.

We claim:

The ornamental design for the combined clock and radio cabinet, as shown and described.
